UNITED STATES PATENT OFFICE.

JOSEPH F. JONES, OF LA GRANGE, ILLINOIS.

DESIGN FOR A VELOCIPED.

53,127.

Specification for Design.

Patented Mar. 25, 1919.

Application filed November 9, 1917. Serial No. 201,178. Term of patent 7 years.

To all whom it may concern:

Be it known that I, JOSEPH F. JONES, a citizen of the United States, residing at La Grange, in the county of Cook and State 5 of Illinois, have invented a new, original, and ornamental Design for a Velocipede, of which the following is a specification, reference being had to the accompanying drawing, forming a part thereof.

10 Figure 1 is a plan view of a velocipede embodying the design;

Fig. 2 is a side elevation thereof.

I claim:

The ornamental design for a velocipede, as shown.

JOSEPH F. JONES.
